UNITED STATES PATENT OFFICE.

MIDDLETON CUNDIFF, OF CENTREVILLE, TEXAS, ASSIGNOR OF TWO-THIRDS
TO ROBERT W. STEVENS AND DEWITT C. MCCOY, OF SAME PLACE.

CAR-COUPING.

SPECIFICATION forming part of Letters Patent No. 498,242, dated May 30, 1893.

Application filed January 24, 1893. Serial No. 459,542. (No model.)

To all whom it may concern:

Be it known that I, MIDDLETON CUNDIFF, a citizen of the United States, residing at Centreville, in the county of Leon and State of Texas, have invented a new and useful Car-Coupling, of which the following is a specification.

The invention relates to improvements in car couplings.

10 The object of the present invention is to improve the construction of car couplings, and to provide a simple and effective one, capable of coupling automatically, and of being uncoupled and set for coupling without necessitating persons going between cars.

15 The invention consists in the construction and novel combination and arrangement of parts hereinafter fully described, illustrated in the accompanying drawings and pointed out in the claim hereto appended.

20 In the drawings—Figure 1 is a perspective view of a car coupling constructed in accordance with this invention. Fig. 2 is a longitudinal sectional view.

25 Like numerals of reference indicate corresponding parts in both the figures of the drawings.

1 designates a draw-head having a coupling pin perforation 2 in its bottom and a coupling pin slot 3 in its top, and provided with a longitudinally disposed partition 4, which is horizontally disposed and forms upper and lower compartments, adapted for the reception of upper and lower spring actuated slides 5 and 6.

30 The horizontal partition 4 is preferably bolted to the sides of the draw-head, and has its front end beveled to form partially the upper portion of the flaring mouth of the draw-head. The upper and lower slides, which are arranged

35 respectively in the upper and lower compartments of the draw-head, have their rear ends bifurcated and are pivotally connected to the ends of an upright lever 7, which is fulcrumed intermediate of its ends in an opening in the horizontal partition near the rear end thereof.

40 A spiral spring 8 is interposed between the front end of the upper slide and the front of the draw-head, and it has its rear end seated in a recess in the front end of the upper slide 5. The spring 8 is adapted to move the upper slide rearward and the lower slide for-

ward, and is adapted to hold the slides normally with the upper one at the rear end of its movement and the lower one advanced. The horizontal partition is provided with a 55 perforation 9 located directly over the coupling pin perforation 2, and the upper slide 5 is provided with a perforation 10 adapted to receive and form a socket for a coupling pin 11 preparatory to coupling, when the slide 5 is moved back. The slot 3 is disposed longitudinally of the draw-head and permits the coupling pin to move forward with the slide 5 to bring it directly over the perforation 9 of the horizontal partition and the perforation 65 2 of the draw-head to permit the coupling pin to fall and engage the link 12. A link entering the draw-head will come in contact with the lower slide, and as two cars come together the slide will be moved rearward and 70 will cause the upper slide 5 to be advanced to carry the coupling pin forward over the perforations 9 and 2, thereby causing the coupling pin to drop and couple with the link.

The coupling pin may be moved forward by 75 hand by means of an operating lever 13, having its lower end fulcrumed on one side of the draw-head and its upper end shaped into a handle and connected with the upper slide by a bolt 14, which is arranged in a longitudinal slot 15 of the adjacent side of the draw-head.

The operation of uncoupling may be performed from the top of a car by means of a lifting lever 16, which is fulcrumed on a 85 bracket 17 and which is connected with the coupling pin by a rod 18.

It will be seen that the car coupling is simple, inexpensive and effective, that it is automatic in its operation and does not necessitate persons going between cars either in the operation of coupling or uncoupling.

Changes in the form, proportion and the minor details of construction may be resorted to without departing from the principle or 95 sacrificing any of the advantages of this invention.

What I claim is—

In a car coupling, the combination of a draw-head provided at one side with a longitudinal 100 slot, upper and lower slides mounted in the draw-head, the upper one being provided with

a perforation to receive a coupling pin and the latter being adapted to be engaged by a link, a lever fulcrumed intermediate of its ends and having its ends connected with the 5 slide to cause the same to move simultaneously, a spring for holding the lower slide at the front of the draw-head and the upper slide at the back thereof, a lever having its lower end fulcrumed on the draw-head, and 10 a bolt arranged in said slot and connecting

the lever with the upper slide, substantially as described.

In testimony that I claim the foregoing as my own I have hereto affixed my signature in the presence of two witnesses.

MIDDLETON CUNDIFF.
